REVERSE LOCK SLIDER FOR SEPARABLE
FASTENERSLouis H. Morin and Davis Marinsky, Bronx, N. Y.,
assignors to Whitehall Patent's Corporation,
Bronx, N. Y., a corporation of New York

Application January 24, 1939, Serial No. 252,534

7 Claims. (Cl. 24—205.5)

This invention relates to separable fasteners employing stringers and particularly to what is termed a lock slider for fasteners of this kind for retaining the slider against movement on the stringers. More particularly, the invention relates to a reversible pin lock slider of this type wherein the lock pin or pin element is capable of movement into engagement with one of the stringers when the pull is arranged adjacent the slider wall in either of two positions. The novel features of the invention will be best understood from the following description when taken together with the accompanying drawing, in which certain embodiments of the invention are disclosed, and in which the separate parts are designated by suitable reference characters in each of the views, and in which:

Fig. 1 is a face view of one form of slider which we employ showing the same arranged upon a portion of two stringers with part of the construction broken away.

Fig. 2 is a partial section on the line 2—2 of Fig. 1, and

Fig. 3 is a perspective view of a modified form 25 of pin mounting which we employ.

In the construction of reversible lock sliders of the class under consideration, it has been the practice to employ locking elements arranged on two surfaces of a pull or in more cases to provide some type of camming means for firmly retaining a lock element in operative position. In such constructions, the locking means has not proved to be satisfactory or fool-proof in that subjecting the stringers to lateral stress tending to move the slider longitudinally thereof would invariably cause the camming means or the pin means integral with the pull to be forced out of operative position. This is especially true when the pull is arranged in the so-called reverse position; that is to say, when the pull extends in the direction of the wide end of the slider. It is the purpose of the present invention to provide a pin locking means which will overcome the objections to devices of the kind now commonly employed in providing a pin element for engaging the fastener stringers which is movably supported upon the pull and adapted to be moved into and out of the channel of the slider. The pull serves primarily to move the pin element into its operative and inoperative positions, while at the same time leaving the pin element free for independent movement with respect to the finger piece or pull in the several positions thereof. In other words, the strain upon the pin element when the slider is subjected to accidental opening by stress or

strain is taken up substantially entirely by the pin element without transmission to the finger piece or pull.

In Figs. 1 and 2 of the drawing is shown one embodiment of the invention; and in Fig. 1, is illustrated at 10, 10a a part of two stringers having coupling links or scoops 11, 11a, attached to adjacent edges thereof in the usual manner. At 12 is shown a slider having a projecting bearing member 13 on the upper wall thereof intermediate the narrow and wide ends of the slider; said wall being also provided with an aperture 14 adjacent the bearing 13 and at one side thereof. The bearing 13 is apertured to receive a pivot pin 15 which also passes through or is coupled with the forked end 16 of a finger piece or pull 17, the pin 15 forming a pivot axis around which the pull 17 is free to swing as indicated in the full and dotted line positions of Fig. 2 of the drawing. The positions extending in opposite directions along the slider wall may be referred to as terminal positions of the pull. The pin may be secured either in the bearing 13 or in the forked end 16 of the pull as may be desired. At one side of the pull 17 and in close proximity to the arrangement of the pin 15 therein is an outwardly projecting pin 18 forming a bearing and mounting for a pin or lock element 19 having a more or less reduced or pointed end 20 which is adapted to extend into the channel 21 of the slider to engage the links of one of the stringers, for example, the links 11a of the stringer 10a in the construction shown.

At this time it will be understood, however, that the element 19 may be disposed on either side of the pull, or if desired, two of such elements may be employed and so-mounted as to provide a staggered arrangement of the pointed ends 20 to engage the staggered arrangement of links on opposed stringers as will be apparent. The walls of the aperture 14 are flared outwardly so as to receive the element 19 when the finger piece or pull 17 is arranged substantially parallel to the slider in either of the locked or terminal positions thereof as is clearly indicated in Fig. 2 of the drawing.

In the use of the device as shown in Figs. 1 and 2, it will be understood that when a stress or strain on the stringers occurs which would tend to move the slider longitudinally of the stringers to open the same, the link or links engaging the pointed end 20 of the lock pin or element 19 will cause said end to be jammed between the link and the top wall of the slider especially as shown in the full line position of the parts in Fig. 2

whereas in the reverse dotted line position, the pointed end portion 20 of the elements which swings on its pivot 18 will be forced against the wall of the aperture 14 in the slider to likewise 5 lock the slider against movement. The pivotal mounting of the element 19 provides a free and independent movement of the element without transmitting movement to the pull contrary in this respect to the conventional pin lock sliders 10 where the pin lock element is an integral part of or is rigidly united with the pull.

In Fig. 3 of the drawing a slight modification of the structure shown in Figs. 1 and 2 is illustrated. This modification consists simply in providing a recess 22 in one side of a finger piece or pull 17a at the forked end 16a thereof and in utilizing a pin element 19a of a thickness corresponding to the depth of the recess 22 so that the outer surface of the element 19a will be in 15 alignment with the outer side surface of the pull proper. The element 19a is pivoted on a pin 18a protruding from one of the forked ends 16a. While a large clearance is shown between the pivot end of the element 19a and the wall 23 of the 20 recess 22 in the accompanying drawing, this is merely for clearness of illustration; and it will be understood that the wall 23 may be arranged in close proximity to the element 19a and even conform with the rounded contour of the pivoted 25 end thereof.

From the foregoing it will appear that in the construction disclosed, the lock element may be said to have a free and independent movement with respect to the finger piece or pull especially 30 in the movement thereof into locked position; whereas a coupling is provided between the element and the finger piece or pull to positively withdraw the element from its locked position automatically in the operation of raising the finger 35 piece or pull in the manual movement of the slider longitudinally of the stringers in either direction. In this connection, it will be understood that it is not essential that the finger piece or pull be fully raised in order to accomplish the operation 40 of the slider. Sufficient clearance will be allowed between the lock element and the links to disengage the links when the finger piece or pull is raised sufficiently to grasp the same in the desired operation. The latter will be understood 45 when it is realized that the greatest movement is attributed to the lock element in the early stages of the lifting operation of the pull, whereas the degree of this lifting motion decreases as the pull is brought into the perpendicular position.

50 It will be understood that our invention is applicable for use in connection with various forms of metallic fasteners as well as in the use of metallic sliders upon the non-metallic or thermoplastic stringers. In fact, the entire slider may be composed of thermoplastic material where this type of a locking means is desirable on all thermoplastic fasteners.

Having fully described our invention, what we 55 claim as new and desire to secure by Letters Patent, is:

1. A lock slider for separable fastener stringers of the character described, said slider having spaced walls joined at one end by a connecting web forming diverging channels therebetween, bearing forming means on the outer surface of one top wall of said slider, a pull pivotally secured at one end thereof to said bearing forming means and adapted when arranged in either of two terminal positions to extend along the top 60 wall of the slider in parallel relation thereto, the

top wall of said slider having an aperture therein in spaced relation to and in transverse alignment with said bearing forming means, said pull being provided with a movable lock element registering with the aperture in said slider wall and adapted 5 in either terminal position of said pull to operatively extend into the channel of said slider, said lock element comprising a substantially wedge-shaped member pivotally secured to one side edge of said pull, and the end walls of the aperture in 10 said slider being sharply beveled to conform with the wedge-like contour of said lock element when in the locked position.

2. A lock slider for separable fastener stringers of the character described, said slider having 15 spaced walls joined at one end by a connecting web forming diverging channels therebetween, bearing forming means on the outer surface of one top wall of said slider, a pull pivotally secured at one end thereof to said bearing forming means 20 and adapted when arranged in either of two terminal positions to extend along the top wall of the slider in parallel relation thereto, the top wall of said slider having an aperture therein in spaced relation to and in transverse alignment 25 with said bearing forming means, said pull being provided with a movable lock element registering with the aperture in said slider wall and adapted in either terminal position of said pull to operatively extend into the channel of said slider, 30 said lock element comprising a substantially wedge-shaped member pivotally arranged on a projecting pin at one side edge of said pull, the side edge of said pull adjacent said pin being recessed to provide arrangement of said lock element within the boundary defined by the side edges of said pull.

3. A lock slider for separable fastener stringers of the character described, said slider having spaced walls joined at one end by a connecting 40 web forming diverging channels therebetween, bearing forming means on the outer surface of one top wall of said slider, a pull pivotally secured at one end thereof to said bearing forming means and adapted when arranged in either of two terminal 45 positions to extend along the top wall of the slider in parallel relation thereto, the top wall of said slider having an aperture therein in spaced relation to and in transverse alignment with said bearing forming means, said pull having a movable lock element registering with the aperture in said slider wall and adapted in either terminal position of said pull to operatively extend into the channel of said slider, said lock element comprising a substantially wedge-shaped member, a pivot 50 coupling for said member on said pull between the pivot of the pull and the free end thereof, and the spaced relation of said pivot coupling and the pivot mounting end of said pull being sufficient to provide withdrawal of said lock element from the channel of said slider when the pull is raised 55 from its terminal position to operate said slider.

4. In a lock slider, a channeled slider body having spaced walls, a pull pivoted at one end thereof to the slider body and movable between two terminal positions extending in opposite directions along one wall of the slider, a tapered lock element, means pivotally coupling said element to said pull between the pivot end thereof and the free end of the pull, said wall of the 70 slider having an aperture adjacent the pivot end of the pull, and the tapered end of said element in either terminal position of said pull extending through said aperture, and into the channel 75 of said slider.

5. In a lock slider, a slider body having spaced walls, a pull pivoted at one end thereof to the slider body and movable between two terminal positions extending in opposite directions along 5 one wall of the slider, a lock element having a wide end and a pointed end, means pivotally coupling the wide end of said element with said pull between the pivot end thereof and the free end of the pull, said wall of the slider having an 10 aperture adjacent the pivot end of the pull, the other pointed end of said lock element extending into said aperture, and the spaced relation of said means and the pivot end of said pull being sufficient to provide for the extension of the pivot 15 end of the lock element through the aperture and under said slider wall in either terminal position of the pull.

6. A lock slider for separable fastener stringers of the character described, said slider having 20 spaced walls joined at one end by a connecting web forming diverging channels therebetween, bearing forming means on the outer surface of one top wall of said slider, a pull pivotally secured at one end thereof to said bearing forming means 25 and adapted when arranged in either of two terminal positions to extend along the top wall of the slider in parallel relation thereto, the top wall of said slider having an aperture therein in spaced relation to and in transverse alignment with said bearing forming means, a lock element having 30

a fixed pivot axis on the pull between the pivot of the pull and the free end thereof, and said lock element having a portion constantly maintained in said aperture of the slider wall and adapted in either terminal position of said pull to operatively extend into the channel of said slider. 5

7. A lock slider for separable fastener stringers of the character described, said slider having spaced walls joined at one end by a connecting web forming diverging channels therebetween, 10 bearing forming means on the outer surface of one top wall of said slider, a pull pivotally secured at one end thereof to said bearing forming means and adapted when arranged in either of two terminal positions to extend along the top wall of 15 the slider in parallel relation thereto, the top wall of said slider having an aperture therein in spaced relation to and in transverse alignment with said bearing forming means, said pull having a movable lock element registering with the aperture in 20 said slider wall and adapted in either terminal position of said pull to operatively extend into the channel of said slider, said lock element comprising a substantially wedge-shaped member, and means forming a fixed pivot for said member 25 to one side of the pull between the pivot end of the pull and the free end thereof.
